Primary Examiner — Susan E Krakower(74) *Attorney, Agent, or Firm* — The Miller Law Offices PLC; Steven J. Miller, Esq.**CLAIM**

The ornamental design for an upper body exercise device, as shown and described.

DESCRIPTION

FIG. 1 is a perspective view of the topside of an upper body exercise device;

FIG. 2 is a side elevation view thereof;

FIG. 3 is an end elevation view thereof;

FIG. 4 is a top plan view thereof; and,

FIG. 5 is a bottom plan view thereof.

The broken lines illustrate portions of the upper body exercise device which form no part of the claimed design.
